(57) **CLAIM**

The ornamental design for a device mount, as shown and described.

DESCRIPTION

FIG. 1 is a perspective view of the first embodiment of the device mount according to the invention, showing the front, top, and side.

FIG. 2 is a perspective view of the first embodiment of the device mount showing the back, bottom, and side.

FIG. 3 is front plan view of the device mount.

FIG. 4 is a left side plan view of the device mount.

FIG. 5 is a back plan view of the device mount.

FIG. 6 is a right side plan view of the device mount.

FIG. 7 is a top plan view of the device mount.

FIG. 8 is a bottom plan view of the device mount; and, FIG. 9 is a cross-sectional view of the device mount taken from line 9-9 in FIG. 7.

The broken lines represent cross-section markers and form no part of the claim.
